(57) **CLAIM**

The ornamental design for a train toy, as shown.

DESCRIPTION

FIG. 1 is a front perspective view of the train toy showing my design;

FIG. 2 is rear perspective view thereof;

FIG. 3 is front view thereof;

FIG. 4 is rear view thereof;

FIG. 5 is a left side view thereof;

FIG. 6 is right side view thereof;

FIG. 7 is a top view thereof;

FIG. 8 is bottom view thereof; and,

FIG. 9 is a perspective view thereof with a front compartment opened.

The broken line showing of a toy figure is included for the purpose of illustrating environmental structure and forms no part of the claimed design.
